RECLINING CHAIR

Fridtjof F. Schliephacke, Berlin-Schmargendorf, Germany, assignor to Anton Lorenz, Boynton Beach, Fla.
Filed Oct. 4, 1961, Ser. No. 142,804
8 Claims. (Cl. 297—85)

The present invention relates to reclining chairs of the type including a body-supporting means having a seat and back-rest and leg-rest mounted on a support for coordinated movement, and in particular to an improved leg-rest and control arrangement for a reclining chair in which the back-rest and seat are movable from a sitting position on an intermediate, tilted sitting position in which the back-rest and seat are in an angular relationship for accommodating the occupant in a partially reclined or resting attitude, and in which the back-rest and seat movable into a fully reclining position in which the back-rest and seat are disposed for accommodating the chair occupant in a fully reclined attitude.

The well known reclining chair comprises a support, body-supporting means including a seat and back-rest movably or rockably mounted on the support, and a leg-rest appropriately coordinated to the body-supporting means for movement into an elevated leg-supporting position as a function of the reclining movement of the chair. One of the most recent developments in such chairs is a reclining chair which is designed to provide an intermediate, tilted sitting position for the chair occupant, suitable for reading, television viewing and the like, as well as the fully reclined position suitable for complete or total relaxation. In such "multiple movement" chairs it is important that the leg-rest be elevated into a leg-supporting position forwardly of the seat when the body-supporting means of the chair moves into the intermediate, tilted sitting position such that the leg-rest will cooperate with the seat and back-rest to comfortably accommodate the chair occupant in the proper attitude for this mode of relaxation.

It is broadly an object of the present invention to provide an improved leg-rest and control arrangement for a reclining chair of the aforesaid type. Specifically, it is within the contemplation of the present invention to provide a leg-rest control arrangement which employs a drag link mechanism for moving the leg-rest from a stored position beneath the seat to an elevated leg-supporting position in front of the seat during a first movement phase of the body-supporting means during which the seat and back-rest move from a sitting position to an intermediate, tilted sitting position, such that the elevated leg-rest, in conjunction with the seat and back-rest coact to comfortably accommodate the chair occupant in the intermediate, tilted sitting position appropriate for reading, television viewing and like pursuits. Further, the drag link arrangement is so arranged that the drag link mechanism does not cause any appreciable angular change in the relationship between the leg-rest and the body-supporting means during the second movement phase as the seat and back-rest move from the intermediate, tilted sitting position to a fully reclined position.

A further object of the present invention is to provide an improved leg-rest and control arrangement for a reclining chair of the "multiple movement" rester type wherein the back-rest and seat are rigidly secured to each other and for a reclining chair of the "multiple-movement" lounger type wherein the back-rest and seat move relative to each other during the second movement phase to increase the angular relationship therebetween.

The drag link mechanism employed in the present invention is a four-bar linkage including a driver, a follower, a connecting rod interconnecting the driver and follower, and a stationary link. The stationary link of the drag

2

link mechanism employed in the present invention is the support since the driver and the follower are both pivoted to the support. In drag link mechanisms, the driver and the follower are able to make complete turns about their respective centers. However, while the driver initially turns through an angle of more than 180° both the follower and the connecting link turn to an angle of less than 180°. Of course, while the driver completes its turn through an angle of less than 180° the follower and the connecting link also complete their turns, the follower turning through an angle greater than 180°. The present invention contemplates employing the relatively large angular movement of the driver in the first movement phase to cause a corresponding large angular movement of the connecting link thereby lifting the leg-rest from a stored position beneath the seat to an elevated leg-supporting position in front of the seat during the first movement phase. However, during the second movement phase, an equally large angular displacement of the driver will cause 20 no appreciable angular movement of the connecting link and hence no appreciable movement of the leg-rest relative to the body-supporting unit.

In accordance with an illustrative embodiment demonstrating features and advantages of the present invention, 25 there is provided a reclining chair which comprises a support, body-supporting means including a back-rest and seat, a leg-rest, and means mounting the body-supporting means on the support for establishing a first phase of movement from a sitting position to an intermediate, tilted sitting position and for a second phase of movement from the intermediate, tilted sitting position to a reclining position. Leg-rest control means are operatively connected to the leg-rest and includes a driver link pivotally mounted on the support, a follower link pivotally mounted on the support at a location spaced from the driver link and an extensible linkage pivotally connected to the leg-rest. The extensible linkage is pivotally connected to the body-supporting means and includes a first pair of leg-rest links and a second pair of leg-rest links pivotally connected to the first pair of leg-rest links. One of the links of the first and second pairs of leg-rest links is a connecting link extending between and pivoted to the driver link and the follower link. The driver link, the connecting link, the follower link and the support form the four-link drag link mechanism. This drag link mechanism is operative during the first movement phase upon approximately 90° movement of the driver link to move the leg-rest from a stored position beneath the seat to an elevated leg-supporting position in front of the seat and is further operative during the second movement phase upon a further approximately 90° movement of the driver link to raise the leg-rest with no appreciable angular displacement between the leg-rest and the seat. It is noted that the extensible linkage employed 55 is in the form of a double quadric linkage whereby the leg-rest is extended from a stored position closely adjacent and beneath the seat to an elevated leg-supporting position spaced in front of the seat.

The above brief description, as well as other objects, 60 features and advantages of the present invention will be more fully understood by reference to the following detailed description of several illustrative embodiments in accordance with the present invention, when taken in conjunction with the accompanying drawings, wherein:

FIG. 1 is an elevational view, with parts broken away and sectioned, of an improved reclining chair embodying features of the present invention, the chair being shown in its upright sitting position;

FIG. 2 is a view similar to FIG. 1, with the leg-rest control linkage being shown diagrammatically, showing the chair in a partially reclined intermediate, tilted sit-

ting position with the leg-rest disposed in an elevated leg-supporting position forwardly of the seat;

FIG. 3 is a view similar to FIG. 2, but showing the chair in a fully reclined position wherein the back-rest is angularly displaced relative to the seat, and with the leg-rest in an elevated leg-supporting position;

FIG. 4 is an elevational view, with parts broken away and sectioned of a further embodiment of reclining chair in accordance with the present invention, the chair being shown in the upright sitting position and being of the type where the back-rest is pivoted to the support with the seat being pivoted to the back-rest;

FIG. 5 is an elevational view with parts shown diagrammatically, illustrating the reclining chair of FIG. 4 in the partially reclined intermediate, tilted sitting position;

FIG. 6 is an elevational view, with parts broken away and sectioned of the reclining chair shown in FIG. 4 in the fully reclined position;

FIG. 7 is an elevational view, with parts shown diagrammatically, of a further embodiment of reclining chair in accordance with the present invention, the chair being of the "rester" type wherein the back-rest and seat are rigidly connected to each other, the chair being shown in the upright sitting position;

FIG. 8 is an elevational and diagrammatic view similar to FIG. 7, but showing the chair in the partially reclined intermediate, tilted sitting position; and

FIG. 9 is an elevational and diagrammatic view similar to FIG. 7, but showing the chair in the fully reclined position.

With continuing reference to the accompanying drawings wherein like reference numerals designate similar parts throughout the various views, there is shown in FIGS. 1 to 3 inclusive an illustrative embodiment of the invention comprising an improved reclining chair generally designated by reference numeral 19, which includes a chair frame or support 12 having spaced apart walls or members 14 connected by suitable cross braces 16. The chair frame 12 is supported above the level of the floor by four depending legs 18. Movable or rockably mounted on the chair frame or support 12 is the body-supporting means 20 including a back-rest 22 and a seat 24. The back-rest 22 is mounted adjacent to its lower end for rearward or reclining movement on a back-rest pivot 26 on the chair frame 12 such that the back-rest 22 may be moved from an upright or sitting position of FIG. 1 into the partially reclined intermediate, tilted sitting position of FIG. 2 and into the fully reclined position of FIG. 3. The seat 24 is mounted on the back-rest for inclining movement by seat pivot 28 on the back-rest, the seat pivot 28 being spaced above the back-rest pivot 26 such that the seat moves rearwardly in response to a rearward or reclining movement of the back-rest 22. In this embodiment, the seat pivot 28 is displaced forwardly of a dead center position vertically of the back-rest pivot 26 such that the rear portion of the seat 24 is somewhat elevated in response to the reclining movement into the intermediate, tilted sitting position, as may be appreciated by progressively inspecting FIGS. 1 and 2, and is thereafter somewhat lowered in response to reclining movement into the fully reclined position, as may be appreciated by progressively inspecting FIGS. 2 and 3.

Operatively connected to or engaging the seat 24 is a seat control means, generally designated by reference numeral 30, which is effective to impart a prescribed inclination to the seat 24 as a function of the reclining movement. In this illustrative embodiment, the seat control means 30 includes a cam plate 32 appropriately connected to the chair frame 12 and formed on its upper surface with an upwardly and rearwardly directed cam track 34 having spaced dwell sections 34a, 34b, and 34c. Riding on the cam track 34 is a roller 36 which is jour-

naled on an axle 38 carried on the underside of the seat 24 by an appropriate mounting bracket.

In the upright sitting position of the chair illustrated, in FIG. 1, the roller 36 is in the lower dwell section 34a; and in response to a first phase of the reclining movement the roller moves up the cam track into the intermediate dwell section 34b. The inclination of the cam track 34 and the spacing of the dwell sections 34a, 34b is such that there is no appreciable relative angular displacement between the back-rest 22 and seat 24 as the body-supporting unit 20 moves into the intermediate, tilted sitting position or partially reclined position illustrated in FIG. 2. It will be appreciated that the seat 24 experiences a compound inclining movement as a function of the seat control 30 and the arrangement of the seat pivot 28 relative to the back-rest pivot 26. Although the arrangement illustrated achieves substantially no angular displacement of the seat relative to the back-rest in the first phase of the chair movement from the sitting position to the partially reclined or intermediate, tilted sitting position in FIG. 2, it will be appreciated that proper proportioning and arrangement of the seat control may be established to achieve some angular change as may be required for one purpose or another.

20 In the fully reclined position illustrated in FIG. 3, the roller 36 is in the upper dwell section 34c, the roller moving from the intermediate dwell section 34b in response to movement of the reclining chair through a second movement phase from the intermediate, tilted sitting position of FIG. 2 to the reclining position of FIG. 3. Inclination of the cam track 34 and the spacing of the dwell section 34c relative to the dwell section 34b is selected such that the seat assumes the required angular relationship relative to the back-rest for accommodating 30 the chair occupant in the fully reclined position. It is to be appreciated that seat 24 experiences a compound inclining movement in that the seat pivot 28 moves past the dead center position over the back-rest pivot 26 (see FIG. 2) and is displaced through a somewhat descending arc. By proper proportioning of the seat control 30 in relation to other designed considerations, the back-rest 22 is actually displaced relative to the seat 24 during the second movement phase from the tilted sitting position to the reclining position, such that the chair occupant 40 may be ultimately accommodated in the fully reclined position illustrated in FIG. 3 with the proper relationship between the back-rest and seat for optimum comfort.

45 Folded back beneath the seat 24 contiguous to the forward end thereof is a leg-rest 40 which is disposed in a stored position in an inclining plane extending downwardly and rearwardly from its upper end 40a to its lower end 40b. The inclination of the leg-rest is determined by general design considerations for the chair 50 and is selected such that the leg-rest is accommodated within the chair frame 12 when the chair is in the upright sitting position of FIG. 1, with the upper end 40a of the leg-rest disposed beneath the forward portion or edge 24a of the seat and the lower end 40b of the leg-rest disposed within the outline of the chair and at a level above the undersurface of the chair frame.

55 Actively connected to the leg-rest 40 is a leg-rest supporting and controlling means or linkage, generally designated by reference numeral 42 which moves the leg-rest 40 from a stored position beneath the seat 24 to an elevated leg-supporting position in front of the seat during the first phase of the chair movement as the chair moves into the partially reclined intermediate, tilted sitting position of FIG. 2, with the leg-rest thereafter being supported in the leg-supporting position in front of the seat 24 during the second phase of the chair movement as the chair moves into the fully reclined position illustrated in FIG. 3. The leg-rest supporting and controlling means or linkage 42 includes a seat connecting link 44 which extends substantially lengthwise of the seat and has a

pivotal connection 46 at its rearward end to the seat such that a rearwardly directed thrust is imparted to the seat connecting link 44 in response to rearward and inclining movement of the seat 24. The linkage 42 further includes a first link pair 48, 50 pivotally connected to each other at their adjacent ends at a pivotal connection 52 and a second link pair 54, 56 pivotally connected to each other at their adjacent ends at a pivotal connection 58. The second link 56 of the second link pair 54, 56 crosses over the first link 48 of the first link pair 48, 50 and at the cross over point there is a pivotal connection 62 for coordinating the link pairs.

There is provided a follower link 64 which is pivotally mounted on the chair frame or support 12 for turning movement. Specifically, the follower link 64 is pivoted at its rear end at a pivot 66 on a bracket or support fixed to the chair frame 12. The first link 48 of the first link pair 48, 50 is pivotally connected to the upper end of the follower link 64 at a pivotal connection 68. The pivotal connection 68 is spaced from the coordinating connection 62 between the link pairs, the follower link 64 having its upper end provided with a curved or bent section to facilitate the provision of the pivotal connection 68 between the follower link 64 and the link 48. The first link 54 of the second link pair 54, 56 has a pivotal connection 70 to the follower link 64 at a point spaced from the pivotal connection 68. The links 50, 56 of the first and second link pairs have their forward ends connected to the leg-rest 40 adjacent its upper end at spaced pivotal connections 72, 74. The link pairs are pivotally connected at 76 to the seat connecting link 44 and in this embodiment, the pivotal connection 76 is provided at the upper end of the first link 48 of the first link pair 48, 50. Pivotally mounted on the support 12 at a pivot 78 is a driver link 80 which is pivoted to the links 54, 56 of the second pair of links at their pivot point 58. The driver link 80 together with the first link 54 of the second pair of links 54, 56 and with the follower link 64 form in conjunction with the support 12 a drag link mechanism, it being noted that the pivots 66 and 78 are spaced from each other and this spaced relationship is fixed, the support 12 because of the spacing of the pivot 66 and 78 forming a fixed link for the drag link mechanism. This drag link mechanism is generally indicated at 82 and functions such that during an initial approximately 90° rotation of the driver link 80 from the upright sitting position illustrated in FIG. 1 to the intermediate tilted sitting position illustrated in FIG. 2, there is a corresponding substantial angular movement of the link 54 so that the leg-rest 40 is moved from the position beneath the seat 24 to a position in front of the seat 24. However, the successive approximate 90° rotation of the driver link 80 is such that the connecting link 54 between the driver link 80 and the follower link 64 does not move any appreciable angular amount relative to the seat 24 so that the leg-rest 40 does not move to any appreciable extent angularly with respect to the seat 24. The link 54 of course extends between the driver link 80 and the follower link 64 and serves as the connecting link of the drag link mechanism 82.

The stored position of the leg-rest 40 is determined by the engagement of the link 44 with the stop 84. The stop 84 is preferably fixed to the seat 24.

A typical sequence of operations will now be described to facilitate a more thorough understanding of the present invention:

When an occupant is seated and leans against the back-rest 22, the back-rest 22 pivots about the back-rest pivot 26 in a rearwardly directed arc and a compound movement is imparted to the seat 24 which is inclined in accordance with the design of its control arrangement, with or without angular change between the back-rest 22 and the seat 24 in response to movement from the upright sitting position illustrated in FIG. 1 to the partially reclined intermediate, tilted sitting position illustrated in

FIG. 2. As the body-supporting means 20 moves rearwardly, a rearwardly directed pulling force is applied to the seat connecting link 44 near the pivotal connection 46 which imparts a turning movement to the link 48 causing the leg-rest control linkage to extend and move the leg-rest 40 to the elevated leg-supporting position forwardly of the seat 24 in response to the first phase of the movement, and the seat and back-rest move into the partially reclined intermediate, tilted sitting position of the FIG. 2.

During the first phase of the reclining movement the link 64 remains substantially stationary and the driver link 80 is rotated approximately 90° which in turn rotates the connecting link 54 of the drag link mechanism through almost 90° of rotation. Since the connecting link 54 forms one link of a double quadric linkage or extensible lazy tong defined by these links and their respective pivotal connections to each other and to the leg-rest 40, a movement of the leg-rest 40 is substantially predicated upon movement of the connecting link 54. The chair components are so coordinated and arranged that there is a tendency for the follower link 64 to turn in the clockwise direction about its pivot 66 in response to the second phase of movement, during which the seat and back-rest move from the partially reclined intermediate, tilted sitting position of FIG. 2, with the leg-rest disposed forwardly of the seat, to the fully reclined position illustrated in FIG. 3, with the angle between the back-rest and seat increased and with the leg-rest disposed contiguous to the forward end of the seat. During the second phase of the movement it is to be noted that there is very little movement of the leg-rest supporting and controlling linkage 42, it may be appreciated by progressively inspecting the relative position of the links in FIGS. 2 and 3 and the relative position of the leg-rest 40 and the seat 24. This arises due to the fact that even though the driver link 80 is undergoing approximately 90° of rotation during the second movement phase, the connecting link 54 does not move angularly appreciably with respect to the seat 24 even though the seat is somewhat raised with respect thereto so that very little angular movement, if any, is imparted to the leg-rest 40.

It is noted that inclination of the seat 24 is determined by the seat control 39 and the relationship of the seat pivot 28 to the back-rest pivot 26.

When the chair occupant desires to return from the fully reclined position of FIG. 3 to either the partially reclined intermediate, tilted sitting position of FIG. 2 or the sitting position of FIG. 1, the occupant merely leans forward exerting a downward force on the leg-rest.

In FIGS. 4 to 6 inclusive, there is shown a further reclining chair in accordance with the present invention generally designated by reference numeral 110. In the interest of simplicity and clarity the chair illustrated in FIGS. 4 through 6 has been illustrated by reference numerals which correspond to those employed in FIGS. 1 through 3 and is part of a 100 series.

This embodiment of reclining chair 110 includes a chair frame or support 112 having spaced apart walls or members 114 connected by suitable cross braces 116. The chair frame 112 is supported above the level of the floor by four depending legs 118. Movably or rockably mounted on the chair frame or support 112 is body-supporting means 120 including a back-rest 122 and a seat 124. The back-rest is mounted adjacent its lower end for rearward or reclining movement on a back-rest pivot 125 on the chair frame 112 such that the back-rest 122 may be moved from an upright sitting position of FIG. 4 into the partially reclined intermediate, tilted sitting position of FIG. 5 and into the fully reclined position of FIG. 6. The seat 124 is mounted on the back-rest 122 for inclining movement by seat pivot 128 on the back-rest, the seat pivot 128 being spaced above the back-rest pivot 126 such that the seat moves rearwardly in response to a rearward or reclining movement of the back-

rest 122. In this embodiment, the seat pivot 128 is displaced forwardly of a dead center position vertically of the back-rest pivot 126 such that the rear portion of the seat 124 is somewhat elevated in response to the reclining movement into the intermediate, tilted sitting position, as may be appreciated by progressively inspecting FIGS. 4 and 5, and is thereafter somewhat lowered in response to reclining movement into the fully reclined position, as may be appreciated by progressively inspecting FIGS. 5 and 6.

Operatively connected to or engaging the seat 124 is a seat control means, generally designated by reference numeral 130, which is effective to impart a prescribed inclination to the seat 124 as a function of the reclining movement. In this illustrative embodiment, the seat control means 130 includes a cam plate 132 appropriately connected to the chair frame 112 and formed on its upper surface with an upwardly and rearwardly directed cam track 134 having spaced dwell sections 134a, 134b, and 134c. Riding on the cam track 134 is a roller 136 which is journalled on an axle 138 carried on the underside of the seat 124 by an appropriate mounting bracket.

In the upright sitting position of the chair illustrated in FIG. 4, the roller 136 is in the lower dwell section 134a; and in response to a first phase of the reclining movement the roller 136 moves up the cam track into the intermediate dwell section 134b. The inclination of the cam track 134 and the spacing of the sections 134a, 134b is such that there is no appreciable relative angular displacement between the back-rest 122 and the seat 124 as the body supporting means 120 moves into the intermediate, tilted sitting position or partially reclined position illustrated in FIG. 5. It will be appreciated that the seat 124 experiences a compound inclining movement as a function of the seat control 130 and the arrangement of the seat pivot 128 relative to the back-rest pivot 126. Although the arrangement illustrated achieves substantially no angular displacement of the seat relative to the back-rest in the first phase of the chair movement from the sitting position to the partially reclined intermediate, tilted sitting position in FIG. 5, it will be appreciated that proper proportioning and arrangement of the seat control may be established to achieve some angular change as may be required for one purpose or another.

In the fully reclined position illustrated in FIG. 6, the roller 136 is in the upper dwell section 134c, the roller moving from the intermediate dwell section 134b in response to movement of the reclining chair through a second movement phase from the intermediate, tilted sitting position of FIG. 5 to the fully reclined position of FIG. 6. Inclination of the cam track 134 and the spacing of the dwell section 134c relative to the dwell section 134b is selected such that the seat assumes the required angular relationship relative to the back-rest for accommodating the chair occupant in the fully reclined position. It is to be appreciated that seat 124 experiences a compound inclining movement in that the seat pivot 128 moves past the dead center position over the back-rest pivot 126 (see FIG. 5) and is displaced through a somewhat descending arc. By proper proportioning of the seat control 130 in relation to other designed considerations, the back-rest 122 is actually displaced relative to the seat 124 during the second movement phase from the intermediate tilted sitting position to the reclining position, such that the chair occupant may be ultimately accommodated in the fully reclined position illustrated in FIG. 6 with the proper relationship between the back-rest and seat for optimum comfort.

Folded back beneath the seat 124 contiguous to the forward end thereof is a leg-rest 140 which is disposed in a stored position in an inclining plane extending downwardly and rearwardly from its upper end 140a to its lower end 140b. The inclination of the leg-rest is determined by general design considerations for the chair and is selected such that the leg-rest is accommodated within

the chair frame 112 when the chair is in the upright sitting position of FIG. 4, with the upper end 140a of the leg-rest disposed beneath the forward portion or edge 124a of the seat and the lower end 140b of the leg-rest disposed within the outline of the chair and at a level above the undersurface of the chair frame.

Actively connected to the leg-rest 140 is a leg-rest mounting and controlling means or linkage, generally designated by reference numeral 142 which moves the leg-rest 140 from a stored position beneath the seat 124 to an elevated leg-supporting position in front of the seat during the first phase of the movement as the body-supporting means 120 moves into the partially reclined intermediate, tilted sitting position of FIG. 5, with the leg-rest thereafter being supported in the leg-supporting position in front of the seat 124 during the second phase of the movement as the seat and back-rest moves into the fully reclined position illustrated in FIG. 6. The leg-rest supporting and controlling means or linkage 142 includes a seat connecting link 144 which extends substantially lengthwise of the seat and has a pivotal connection 146 at its rearward end to the seat such that a rearwardly directed thrust is imparted to the seat connecting link 144 in response to rearward and inclining movement of the seat 124. The linkage 142 further includes a first link pair 148, 150 pivotally connected to each other at their adjacent ends at a pivotal connection 152 and a second link pair 154, 156 pivotally connected to each other at their adjacent ends at a pivotal connection 158. The first link 154 of the second link pair 154, 156 crosses over the second link 150 of the first link pair 148, 150 and at the cross-over point there is a pivotal connection 162 for coordinating the link pairs. The free end of link 154 is pivotally connected to the seat 124 at the pivotal connection 163.

There is provided a follower link 164 which is pivotally mounted on the chair frame or support 112 for turning movement. Specifically, the follower link 164 is pivoted at its rear end at a pivot 166 on a bracket or support fixed to the chair frame 112. The first link 148 of the first link pair 148, 150 is pivotally connected to the upper end of the follower link 164 at a pivotal connection 168. The pivotal connection 168 is spaced from the coordinating connection 162 between the link pairs, the follower link 164 having its upper end provided with a curved or bent section to facilitate the provision of the pivotal connection 168 between the follower link 164 and the link 148.

The links 150, 156 of the first and second link pairs have their forward ends connected to the leg-rest 140 adjacent its upper end at spaced pivotal connections 172, 174. The link pairs are pivotally connected at 176 to the seat connecting link 144 and in this embodiment, the pivotal connection 176 is provided at the upper end of the first link 148 of the first link 148, 150. Pivotally mounted on the support 112 at a pivot 178 is a driver link 180 which is pivoted to the links 148, 150 of the first pair of links at their pivot point 152. The driver link 180 together with the first link 148 of the first pair of links 148, 150 and with the follower link 164 form in conjunction with the support 112 a drag link mechanism, it being noted that the pivots 166 and 178 are spaced from each other and this spaced relationship is fixed, the support 112 because of the spacing of the pivot 166 and 178 forming a fixed link for the drag link mechanism. This drag link mechanism is generally indicated at 182 and functions such that during an initial approximate 90° rotation of the driver link 180 from the upright sitting position illustrated in FIG. 4 to the intermediate, tilted sitting position illustrated in FIG. 5, there is a corresponding substantial angular movement of the link 148 so that the leg-rest 140 is moved from the position beneath the seat 124 to a position in front of the seat 124. However, the successive approximate 90° rotation of the driver link 180 is such that the connecting link 144 between the driver

link 180 and the follower link 164 does not move any appreciable angular amount relative to the seat 124 so that the leg-rest 140 does not move to any appreciable extent angularly with respect to the seat 124. The link 148 of course extends between the driver link 180 and the follower link 164 and serves as the connecting link of the drag link mechanism 182.

A typical sequence of operations will now be described to facilitate a more thorough understanding of the present invention:

When an occupant is seated and leans against the back-rest 122, the back-rest 122 pivots about the back-rest pivot 126 in a rearwardly directed arc and a compound movement is imparted to the seat 124 which is inclined in accordance with the design of its control arrangement, with or without angular change between the back-rest 122 and the seat 124 in response to movement from the upright or sitting position illustrated in FIG. 4 to the partially reclined intermediate, tilted sitting position illustrated in FIG. 5. As the body-supporting means 120 moves rearwardly, a rearwardly directed pulling force is applied to the seat connecting link 144 near the pivotal connection 146 which imparts a turning movement to the link 148 causing the leg-rest control linkage to extend and move the leg-rest 140 to the elevated leg-supporting position forwardly of the seat 124 in response to the first phase of the chair movement, and the seat and back-rest move into the partially reclined intermediate, tilted sitting position of the FIG. 5.

During the first phase of the reclining movement the link 164 remains substantially stationary and the driver link 180 is rotated approximately 90° which in turn rotates the connecting link 148 of the drag link mechanism through almost 90° of rotation.

Since the connecting link 148 forms one link of a double quadric linkage or extensible lazy tong defined by these links and their respective pivotal connection to each other and to the leg-rest 140, a movement of the leg-rest 140 is substantially predicated upon movement of the connecting link 148. The chair components are so co-ordinated and arranged that there is a tendency for the follower link 164 to turn in the clockwise direction about its pivot 166 in response to the second phase chair movement, during which the seat and back-rest move from the partially reclined intermediate, tilted sitting position of FIG. 5, with the leg-rest disposed forwardly of the seat, to the fully reclined position illustrated in FIG. 6, with the angle between the back-rest and seat increased and with the leg-rest disposed contiguous to the forward end of the seat. During the second phase of the movement it is to be noted that there is very little movement of the leg-rest supporting and controlling linkage 142, it may be appreciated by progressively inspecting the relative position of the links in FIGS. 5 and 6 and the relative position of the leg-rest 140 and the seat 124. This arises due to the fact that even though the driver link 180 is undergoing approximately 90° of rotation during the second movement phase, the connecting link 148 does not move angularly appreciably with respect to the seat 124 even though the seat is somewhat raised with respect thereto so that very little angular movement, if any is imparted to the leg-rest 140.

It is noted that inclination of the seat 124 is determined by the seat control 130 and the relationship of the seat pivot 128 to the back-rest pivot 126.

When the chair occupant desires to return from the fully reclined position of FIG. 6 to either the partially reclined intermediate, tilted sitting position of FIG. 5 or the sitting position of FIG. 4, the occupant merely leans forward exerting a downward force on the leg-rest.

In FIGS. 7 to 9 inclusive, there is shown a further embodiment reclining chair in accordance with the present invention generally designated by reference numeral 210. This reclining chair is of the "rester" type in which the back-rest and seat are rigidly connected to each other.

In the interest of simplicity and clarity the chair illustrated in FIGS. 7 through 9 has been illustrated by reference numerals which correspond to those employed in FIGS. 1 through 3 and is part of a 200 series.

5 The chair 210 includes a chair frame or support 212 having spaced apart walls or members 214 connected by suitable cross braces 216. The chair frame 212 is supported above the level of the floor by four depending legs 218. Movable or rockably mounted on the chair frame or support 212 is body-supporting means in the form of a body-supporting unit 220 including a rigidly connected back-rest 222 and a seat 224. The body-supporting unit is mounted for rearward or reclining movement on the chair frame 212 such that the body-supporting unit may be moved from an upright sitting position of FIG. 7 into the partially reclined intermediate, tilted sitting position of FIG. 8 and into the fully reclined position of FIG. 8. The body-supporting unit 220 is mounted on the frame 212 for inclining movement by a rear link 226 connected to the body-supporting unit at a pivotal connection 227. The rear link 226 is pivoted to the support at pivotal connection 228. In this embodiment, the pivotal connection 227 is displaced forwardly of a vertical dead center position of the link 226 such that the body-supporting unit is somewhat elevated in response to the reclining movement into the intermediate, tilted sitting position, as may be appreciated by progressively inspecting FIGS. 7 and 8, and is thereafter somewhat lowered in response to reclining movement into the fully reclined position, as may be appreciated by progressively inspecting FIGS. 8 and 9.

Operatively connected to or engaging the seat 224 is a seat stop means, generally designated by reference numeral 230, which is effective to impart stopping at a prescribed inclination to the seat 224 as a function of the reclining movement. In this illustrative embodiment, the seat stop means 230 includes a cam plate 232 appropriately connected to the chair frame 212 and formed on its upper surface with an upwardly and rearwardly directed cam track 234 having spaced dwell sections 234a, 234b, and 234c. Riding on the cam track 234 is a roller 236 which is journaled on an axle 238 carried on the underside of the seat 224 by an appropriate mounting bracket.

45 In the upright or sitting position of the illustrated embodiment, in FIG. 7, the roller 236 is in the lower dwell section 234a; and in response to a first phase of the reclining movement the roller moves up the cam track into the intermediate dwell section 234b. It will be appreciated that the body-supporting unit 220 experiences a compound inclining movement as a function of the rear link 226 and the seat stop 230 maintains the seat 224 in the intermediate, tilted sitting position, illustrated in FIG. 8.

55 In the fully reclined position illustrated in FIG. 9, the roller 236 is in the upper dwell section 234c, the roller moving from the intermediate dwell section 234b in response to movement of the reclining chair through a second movement phase from the intermediate, tilted sitting position of FIG. 8 to the fully reclined position of FIG. 9. Inclination of the cam track 234 and the spacing of the dwell section 234c relative to the dwell section 234b is selected such that the body-supporting unit 220 is stopped in the required angular relationship relative to the support 212 for accommodating the chair occupant in the fully reclined position.

Folded back beneath the seat 224 contiguous to the forward end thereof is a leg-rest 240 which is disposed in a stored position in an inclining plane extending downwardly and rearwardly from its upper end 240a to its lower end 240b. The inclination of the leg-rest is determined by general design considerations for the chair and is selected such that the leg-rest is accommodated within the chair frame 212 when the chair is in the upright sitting position of FIG. 7, with the upper end 240a of the

leg-rest disposed beneath the forward portion or edge 224a of the seat and the lower end 240b of the leg-rest disposed within the outline of the chair and at a level above the undersurface of the chair frame.

Actively connected to the leg-rest mounting 240 is a leg-rest and controlling means or linkage, generally designated by reference numeral 242 which moves the leg-rest 240 from a stored position beneath the seat 224 to an elevated leg supporting position in front of the seat during the first phase of the movement as the body-supporting means 220 moves into the partially reclined intermediate, tilted sitting position of FIG. 8, with the leg-rest thereafter being supported in the leg-supporting position in front of the seat 224 during the second phase of the movement as the seat and back-rest move into the fully reclined position illustrated in FIG. 9. The linkage 242 further includes a first link pair 248, 250 pivotally connected to each other at their adjacent ends at a pivotal connection 252 and a second link pair 254, 256 pivotally connected to each other at their adjacent ends at a pivotal connection 258. The second link 256 of the second link pair 254, 256 crosses over the first link 248 of the first link pair 248, 250 and at the cross over point there is a pivotal connection 262 for coordinating the link pairs. There is provided a follower link 264 which is pivotally mounted on the chair frame or support 212 for turning movement. Specifically, the follower link 264 is pivoted at its rear end at a pivot 266 on a bracket or support fixed to the chair frame 212. The first link 254 of the second link pair 254, 256 is pivotally connected to the upper end of the follower link 264 at a pivotal connection 268. The pivotal connection 268 is spaced from the coordinating connection 262 between the link pairs. The first link 254 of the second link pair 254, 256 has a pivotal connection 270 to the seat 224 at a point spaced from the pivotal connection 268. The links 250, 256 of the first and second link pairs have their forward ends connected to the leg-rest 240 adjacent its upper end at spaced pivotal connections 272, 274. The first link 248 of the first link pair is pivotally connected at 276 to the seat 224 and in this embodiment, the pivotal connection 276 being spaced from the pivotal connection 270. Pivotally mounted on the support 212 at a pivot 278 is a driver link 280 which is pivoted to the link 254 of the second pair of links 254, 256 at a pivot point 281. The driver link 280 together with the first link 254 of the second pair of links 254, 256 and with the follower link 264 form in conjunction with the support 212 a drag link mechanism, it being noted that the pivots 266 and 278 are spaced from each other and this spaced relationship is fixed, the support 212 because of the spacing of the pivot 266 and 278 forming a fixed link for the drag link mechanism. This drag link mechanism is generally indicated at 282 and functions such that during an initial approximately 90° rotation of the driver link 280 from the upright sitting position illustrated in FIG. 7 to the intermediate, tilted sitting position illustrated in FIG. 8, there is a corresponding substantial angular movement of the link 254 so that the leg-rest 240 is moved from the position beneath the seat 224 to a position in front of the seat 224. However, the further rotation of the driver link 280 is such that the connecting link 254 between the driver link 280 and the follower link 264 does not move any appreciable angular amount relative to the seat 224 so that the leg-rest 240 does not move to any appreciable extent angularly with respect to the seat 224. The link 254 of course extends between the driver link 280 and the follower link 264 and serves as the connecting link of the drag link mechanism 282.

The sitting position of FIG. 7 is the stop 286 which is fixed to the support 212.

A typical sequence of operations will now be described to facilitate a more thorough understanding of the present invention:

When an occupant is seated and leans against the back-

rest 222, the body-supporting unit pivots about the rear link 226 in a rearwardly directed arc. As the body-supporting unit 220 moves rearwardly an upwardly directed pulling force is applied to the driver link 280 which imparts a turning movement to the link 254 causing the leg-rest control linkage 242 to extend and move the leg-rest 240 to the elevated leg-supporting position forwardly of the seat 224 in response to the first phase of the movement, and the body-supporting unit 220 moves into the partially reclined intermediate, tilted sitting position of the FIG. 8.

During the first phase of the reclining movement the link 264 moves slightly and the driver link 280 is rotated approximately 90° which in turn rotates the connecting link 254 with the drag link mechanism through approximately 90° of rotation. Since the connecting link 254 forms one link of a double quadric linkage or extensible lazy tong defined by these links and their respective pivotal connections to each other and to the leg-rest 240, a movement of the leg-rest 240 is substantially predicated upon movement of the connecting link 254. The components are so coordinated and arranged that there is a tendency for the follower link 264 to turn in the clockwise direction about its pivot 266 in response to the second phase of movement, during which the body-supporting unit 220 moves from the partially reclined intermediate, tilted sitting position of FIG. 8, with the leg-rest disposed forwardly of the seat, to the fully reclined position illustrated in FIG. 9, with the leg-rest disposed contiguous to the forward end of the seat. During the second phase of the movement it is to be noted that there is very little movement of the leg-rest supporting and controlling linkage 242, it may be appreciated by progressively inspecting the relative position of the links in FIGS. 8 and 9 and the relative position of the leg-rest 240 and the seat 224. This arises due to the fact that even though the driver link 280 is undergoing some rotation during the second movement phase, the connecting link 254 does not move angularly appreciably with respect to the seat 224 even though the seat is somewhat raised with respect thereto so that very little angular movement is imparted to the leg-rest 240.

When the chair occupant desires to return from the fully reclined position of FIG. 9 to either the partially reclined intermediate, tilted sitting position of FIG. 8 or the sitting position of FIG. 7, the occupant merely leans forward exerting a downward force on the leg-rest.

Latitude of modification, change and substitution is intended in the foregoing disclosure and in some instances some features of the invention will be employed without a corresponding use of other features. Accordingly, it is appropriate that the appended claims be construed broadly and in a manner consistent with the spirit and scope of the invention herein.

What I claim is:

1. A reclining chair comprising a support, a body-supporting means including a back-rest and seat, means mounting said body-supporting means on said support for establishing a first phase of movement from a sitting position to an intermediate, tilted sitting position and for a second phase of movement from said intermediate, tilted sitting position to a reclining position, a leg-rest, leg-rest control means operatively connected to said leg-rest and including a driver link pivotally mounted on said support, a follower link pivotally mounted on said support at a location spaced from said driver link, an extensible linkage pivotally connected to said leg-rest, means pivotally connecting said extensible linkage to said body-supporting means, said extensible linkage including a first pair of leg-rest links and a second pair of leg-rest links pivotally connected to said first pair, one of the links of said first and second pairs being a connecting link extending between and pivotally connected to said driver link and said follower link, said driver link, said connecting link, said follower link and said support forming a drag link mechanism which

is operative during said first movement phase to move said leg-rest from a stored position beneath said seat to an elevated leg-supporting position in front of said seat and is operative during said second movement phase to raise said leg-rest with no appreciable angular displacement between said leg-rest and said seat.

2. A reclining chair comprising a support, a body-supporting means including a back-rest and seat, means mounting said body-supporting means on said support for establishing a first phase of movement from a sitting position to an intermediate, tilted sitting position and for a second phase of movement from said intermediate, tilted sitting position to a reclining position, a leg-rest, leg-rest control means operatively connected to said leg-rest and including a driver link pivotally mounted on said support, a follower link of greater length than said driver link pivotally mounted on said support at a location spaced from and below the pivoted mount of said driver link, and extensible linkage pivotally connected to said leg-rest, means pivotally connecting said extensible linkage to said body-supporting means, said extensible linkage being a double quadric linkage and including a first pair of leg-rest links and a second pair of leg-rest links pivoted to said first pair, one of the links of said first and second pairs being a connecting link extending between and pivoted to said driver link and said follower link, said driver link, said connecting link, said follower link and said support forming a four bar drag link mechanism which is operative during said first movement phase to move said leg-rest from a stored position beneath said seat to an elevated leg-supporting position in front of said seat and is operative during said second movement phase to raise said leg-rest with no appreciable angular displacement between said leg-rest and said seat.

3. A reclining chair comprising a support, a body-supporting means including a back-rest and seat, means mounting said body-supporting means on said support for establishing a first phase of movement from a sitting position to an intermediate, tilted sitting position and for a second phase of movement from said intermediate, tilted sitting position to a reclining position, a leg-rest, leg-rest control means operatively connected to said leg-rest and including a driver link pivotally mounted on said support, a follower link pivotally mounted on said support at a location spaced from said driver link, an extensible linkage pivotally connected to said leg-rest, means pivotally connecting said extensible linkage to said body-supporting means, said extensible linkage including a first pair of leg-rest links and a second pair of leg-rest links pivoted to said first pair, one of the links of said first and second pairs being a connecting link extending between and pivoted to said driver link and said follower link, said driver link, said connecting link, said follower link and said support forming a drag link mechanism which is operative during said first movement phase upon approximately 90° movement of said driver link to move said leg-rest from a stored position beneath said seat to an elevated leg-supporting position in front of said seat and is operative during said second movement phase upon a further approximately 90° movement of said driver link to raise said leg-rest with no appreciable angular displacement between said leg-rest and said seat.

4. A reclining chair comprising a support, body-supporting means including a back-rest and seat, means pivotally mounting said body-supporting means on said support establishing a first phase of said movement from a sitting position to an intermediate, tilted sitting position and for a second phase of said movement from said tilted sitting position to a reclining position, a leg-rest mounting and controlling means mounting said leg-rest for movement from a stored position beneath said seat to an elevated leg-supporting position in front of said seat during said first phase of said movement, said leg-rest mounting and controlling means including a driver link pivotally mounted on said support, a follower link pivotally

connected to said support, an extensible linkage pivotally connected to said leg-rest and including a connecting link extending between and pivoted to said driver link and said follower link, and means pivotally connecting said extensible linkage to said body-supporting means, said extensible linkage moving said leg-rest into said elevated leg-supporting position in response to movement of said body-supporting means and upon approximately 90° movement of said driver link, there being no appreciable angular change of said connecting link and said leg-rest relative to said seat upon a further approximate 90° movement of said driver link.

5. A reclining chair comprising a support, body-supporting means including a seat and back-rest, means pivotally mounting said body-supporting means on said support and arranged to establish a first movement phase during which said body-supporting means moves from a sitting position to an intermediate, tilted sitting position and a second movement phase from said intermediate, tilted sitting position to a reclining position, a leg-rest, a combined leg-rest mounting and controlling means operatively connected to said leg-rest for mounting and moving said leg-rest from a stored position to an elevated leg-supporting position in response to movement of said body-supporting means into said intermediate, tilted sitting position, said mounting and controlling means including a driver link, means pivotally mounting said driver link on said support for turning movement about a driver pivotal mount, a follower link, means pivotally mounting said follower link on said support for turning movement about a follower pivotal mount, said follower pivotal mount being spaced from said driver pivotal mount, a connecting link pivotally connected to said driver and follower links, leg-rest links pivotally connected to said leg-rest and to at least one of said driver, follower and connecting links and cooperating therewith to mount said leg-rest thereon, and seat connecting means pivotally connected to said seat and to said mounting and controlling means for actuating the latter in response to tilting movement of said seat, said driver link, said follower link, said connecting link and said support forming a drag link mechanism operable during both said first and second movement phase and being effective during said first movement phase upon approximately 90° movement of said driver link to bring about a rapid angular movement of connecting link and of said leg-rest to said elevated leg-supporting position and during said second movement phase upon a further approximate 90° movement of said driver link to bring about substantially no angular change of said connecting link and said leg-rest relative to said seat.

6. A reclining chair comprising a support, body-supporting means including a seat and back-rest, means pivotally mounting said body-supporting means on said support and arranged to establish a first movement phase during which said body-supporting means moves from a sitting position to an intermediate, tilted sitting position and a second movement phase from said intermediate, tilted sitting position to a reclining position, a leg-rest, a combined leg-rest mounting and controlling means operatively connected to said leg-rest for mounting and moving said leg-rest from a stored position to an elevated leg-supporting position in response to movement of said body-supporting means into said intermediate, tilted sitting position, said mounting and controlling means including a driver link, means pivotally mounting said driver link on said support for turning movement about a driver pivotal mount, a follower link, means pivotally mounting said follower link on said support for turning movement about a follower pivotal mount, said follower pivotal mount being spaced from said driver pivotal mount, a first pair of leg-rest links pivotally connected to said leg-rest a second pair of leg-rest links pivotally connected to said leg-rest, one of the links of said first and second pair of links being a connecting link pivotally connected to said driver link and said follower link, said first and second pair of

links being pivotally connected to each other, connected to said seat and to said mounting and controlling means for actuating the latter in response to tilting movement of said seat, said driver link, said follower link, said connecting link, and said support forming a drag link mechanism operable during both said first and second movement phase and being effective during said first movement phase upon approximately 90° movement of said driver link to bring about a rapid angular movement of connecting link and of said leg-rest to said elevated leg-supporting position and up a further approximately 90° movement of said driver link to bring about substantially no angular change of said connecting link and said leg-rest relative to said seat.

7. A reclining chair comprising a support, body-supporting means including a back-rest and seat, means pivotally mounting said body-supporting means on said support, a leg-rest, leg-rest mounting and controlling means mounting said leg-rest for movement from a stored position beneath said seat to an elevated leg-supporting position in front of said seat, said leg-rest mounting and controlling means including a driver link pivotally mounted on said support, a follower link pivotally connected to said support, an extensible linkage pivotally connected to said leg-rest and to said body-supporting means, said extensible linkage including a connecting link extending between and pivoted to said driver link and said follower link, said driver link, follower link and connecting link being arranged relative to each other to produce at least first and second successively different rates of elevation of said leg-rest in response to movement of said body-supporting means, said first rate occurring during a first phase of movement of said body-supporting means and being faster than said second rate and being effective to rapidly move said leg-rest into an elevated leg-supporting position, said second rate occurring during a second phase of movement of said body-supporting means and being effective to maintain said leg-rest in an elevated leg-supporting position.

8. A reclining chair comprising a support, body-supporting means including a back-rest and seat, means pivotally mounting said body-supporting means on said support
